UNITED STATES PATENT OFFICE

GISBERT LUDOLF BOSSARD, OF DAYTON, OHIO, ASSIGNOR TO GENERAL KONTROLAR COMPANY, INC., OF DAYTON, OHIO, A CORPORATION OF OHIO

CHIME

Application filed July 30, 1930. Serial No. 471,814.

This invention relates to musical chimes, and more particularly to chimes that are electrically driven and controlled.

One object of the invention is the provision of an electrically driven chime in which the energizing circuit for an electric motor which drives the chime mechanism is manually controlled.

Another object of the invention is the provision of a chime of sturdy and compact construction adapted to produce a predetermined sequence of musical notes when a controlling electrical contact is closed.

A further object of the invention is the provision of a chime having chime sounding mechanism driven by a single electric motor to produce a predetermined sequence of sounds of various tones, means being provided for starting the motor when desired but so arranged that the motor is open-circuited automatically at the end of the desired sequence of sounds.

Still another object of the invention is the provision of a device for producing a predetermined desired series of notes, the device being compact and of simple and cheap construction and adapted to operate effectively over long periods of time without care or attention.

Other objects and advantages of the invention will be apparent from the following description, the appended claims and the accompanying drawings, in which—

Fig. 1 is a front elevation of an electrical chime embodying the present invention;

Fig. 2 is a side view of the chime operating mechanism, shown partly in section;

Fig. 3 is a front elevation of the chime mechanism;

Fig. 4 is a top plan view of the chime mechanism;

Fig. 5 is a side elevation of the chime mechanism;

Fig. 6 is a section of the chime mechanism on the line 6—6 of Fig. 4;

Fig. 7 is a side view of the motor energizing relay and its associated stopping device;

Fig. 8 is a detail of the stopping device;

Fig. 9 is a diagrammatic representation of the electrical connections;

Fig. 10 is a detailed view partly in section, of the chime hanger; and

Fig. 11 is a top plan view of a chime mechanism, contained in a modified form of housing.

55

Referring more particularly to the drawings, in which preferred forms of the invention are shown, 10, 11, 12 and 13 represent chime sounders, preferably although of course not necessarily in the form of hollow tubes of brass or other suitable metal. When the chime sounders are of tubular form, they are preferably of the same diameter and of different lengths, as shown in Fig. 1, so as to produce tones of different pitch. The

lower ends of the tubes are open, while their upper ends are closed by metal plugs 14 integrally connected at the tops of the tubes. Some little distance below their upper ends, each tube is shown with a pair of small holes 15 through which the suspending cable 16, of loop form, extends. This loop extends up over a triangle of metal or the like 18, the top of which is slotted, and the sides of which project out beyond the sides of the tube so that the cable 16 will not be in contact with the upper end of the tube and thus interfere with the free vibration of the tube. The suspending triangles 18 are hung on pins 19 which project out from a cover plate 20 connected to the supporting housing box 21, and the pins are grooved circumferentially to receive the tops of the cable loops which rest directly in the grooves in the pins, as they extend down through the slots in the

tops of the triangles 18. This form of support definitely locates the chimes with respect to their supporting pins. Preferably the pins are adjustably mounted for axial movement on the cover plate 20. The cover

plate 20 and the housing box 21 are preferably of sheet metal and the cover plate 20 is preferably suitably finished to present a pleasing appearance. A hood 20' is suitably attached to the cover plate 20 and provides an

enclosure for the hangers and upper ends of the chime tubes. As shown, the hood 20' extends the full width of the cover plate and provides a housing having a closed top and

sides, and an open bottom having a defining

95

100

edge some distance below the top of the chime tubes.

The main supporting housing box 21 may be recessed in a wall, indicated at 22, and 5 contains the chime sounding mechanism designated generally 23. The housing box 21 is shown projecting out a little ways from the outer surface of the wall and is overlapped by the rearwardly extending flanges 10 on the cover plate 20, these parts being connected by screws 24 to enclose the chime sounding mechanism and protect the same.

The chime sounders, any desired number of which may be provided, are sounded by 15 hammers 26, 27, 28 and 29 which are so positioned as to strike the tubes 10, 11, 12 and 13 respectively through holes 30 provided in the cover plate 20 of the housing. Each hammer is provided with a striking nose 32, of 20 wood or other suitable material, the nose 32 being held by a nut 33 threaded on the stud 34. The noses 32 are long enough to project through the holes 30 in the housing cover and strike the chime tubes when the hammers are 25 operated, the holes 30 being somewhat larger than the diameter of the striking noses but preferably smaller than the nuts 33. As the only openings in the enclosing housing are the clearance holes 30 for the striking hammers, and these are practically closed by the 30 projecting noses 32 and the adjacent nuts 33 when in normal position, a substantially dust-proof enclosure is provided for the chime actuating mechanism.

35 The hammers 26 to 29 inclusive are operated in predetermined order by means of an electric motor designated generally 36. The armature shaft 37 of the motor carries a flat disc 38 of aluminum or the like which revolves 40 between shaded pole pieces 39 and 40 of an electromagnet 41 formed preferably of strips of laminated soft iron. The poles 39 and 40 are shaded by copper rings 42 and 43 respectively to produce a turning effect 45 on the disc 38 and consequent operation of the armature shaft 37 when the coil 44 of the electromagnet is energized by alternating current. The coil 44 is preferably designed for alternating current of commercial frequency 50 at a low voltage, that is at a voltage very considerably below the ordinary 110 volt value. The energizing circuit for the coil 44, as shown in Fig. 9, includes the wire 55 46, the secondary 47 of a transformer 48, the wire 49, the contact fingers 50 and 51 and the wire 52. When the contact fingers 50 and 51 are closed, the energizing circuit of the electric motor is completed, the primary of transformer 48 being connected to a house wiring circuit of 110 volts or other suitable commercial frequency. The transformer 48 is preferably located at a point remote from the sounding mechanism so that the wires leading 60 to the sounding mechanism and its hous-

ing are of low voltage, minimizing the fire hazard.

The energized circuit of the electric motor is preferably controlled manually from a remote point. The controlling circuit for 70 the energizing circuit includes the manually operable switch or push button 54, a magnet coil 55 and the secondary 47 at the transformer. When the push button 54 is operated to close the controlling circuit, low voltage current is supplied to the magnet coil 55 energizing the same so as to attract its armature 56 which is pivotally mounted at 75 57. One end of the armature 56 is bent upwardly as indicated at 58 and is provided with a knob 59 of insulating material, which, when the magnet coil 55 is energized, presses the contact finger 50 against the contact finger 51 to close the energizing circuit of the electric motor. When the push button 54 is 80 in its open circuit position, the magnet coil 55 is not energized, but suitable means are provided, as will be presently described, to maintain the armature 56 in its attracted position even though the magnet coil 55 is de- 85 energized, until a predetermined sequence of operations has taken place. The armature 56 carries in threaded engagement a brass adjusting screw 56' which is provided to regulate the device for varying operating 90 conditions.

The push button 54 may be provided in the usual location of a door bell of a residence so that the chime can be used for indicating when someone is at the door and 100 wants admittance, this indication being very pleasing and musical as distinguished from the harsh and annoying clatter of a bell, especially when the chime is so designed as to strike the notes of the Westminster chimes 105 or some other pleasing arrangement of notes. It is to be understood, however, that the invention is not limited to this particular use of the chime, as it may be used for giving an indication of any other fact. Thus it may 110 be used as a call for dinner, or manually controlled whenever desired to produce the pleasing notes intended.

When energized, the electric motor turns the shaft 37 which is rotatably mounted in 115 the side plates 60 and 61, the rear ends of which may be held to a back plate 62 by means of angles 63 and suitable attaching screws 64. The back plate 62, which supports the operating mechanism, is adapted 120 to be fastened to the rear side of the housing box 21 by screws 65 or in any other suitable manner, permitting the ready removal of the entire operating mechanism as a unit whenever desired.

On one end of the armature shaft 37 is a pinion 67 which meshes with a gear 68. A pinion 69 fixed to the gear 68 drives gear 70, the power being transmitted by a gear 71 fixed to gear 70 and engaging with gear 72 130

secured by a set screw 73 to a transversely extending shaft 74 which is parallel to the armature shaft and rotatably mounted in the side plates 60 and 61. At each end of the shaft 74 is a pin disc or the like, the two pin discs 75 and 76 each having a series of pins projecting out from each side thereof and arranged in a definite relationship on the disc. Rigid with each of the pin discs 75 and 76 is a hub 77 provided with a set screw 78 which removably or adjustably fastens the pin disc on the shaft.

Below the shaft 74 is a transverse shaft 80 which is rotatably mounted in the side plates 60 and 61 and projects laterally beyond the plates providing a pivotal support for hammer supporting arms 81, 82, 83 and 84. These arms are mounted freely on the shaft 80 and each supports a rod 86 the upper end of which carries a chime hammer. The rods 86 are preferably rather heavy metal wires the upper ends of which may project up through the studs 34 of the hammers to which they are secured by screws 35. One form of connection between the rods 86 and their carrying arms is shown in Fig. 5 for example, the rod being reversely bent through spaced parallel holes in the arm 81, thus rigidly securing the arm to the rod in a simple manner. The rod extends down past its carrying arm and is provided with an upturned end 87 which bears against a long stud 88 suitably fixed to and extending through the side plates 60 and 61. When the upstanding lower end 87 of the hammer rod is in engagement with the stud 88, with the hammer at rest, the nose of the hammer is just slightly spaced away from the adjacent side of its chime tube, but the lower end of the hammer rod has sufficient flexibility, due to its reversely bent form, so that when the hammer is raised and permitted to fall the nose of the hammer will strike the tube and then immediately rebound, being held from striking a second time by the yielding engagement of the upturned end 87 with the stud 88. The arrangement is such that the resiliency in the hammer does not overcome the kinetic energy during striking movements of the hammer but effectively acts against the weight of the hammer when not in motion or when moving only slowly.

The pin disc 75 in Fig. 5 is shown provided with five pins 89, so arranged as to successively push the upper end of the arm 81 to the left during normal clockwise movement of the pin disc. The hammer is shown in its normal position in this figure, but is about ready to be raised by the engagement of the lowest pin 89 with the upper end of the arm 81, and when this occurs the arm 81 will be rocked counterclockwise so as to raise the hammer. Then when the pin passes along and frees the upper end of the arm 81 the hammer will fall due to its weight and strike against the chime tube with which it cooper-

ates. On the other side of the disc 75 is a second series of pins which engage with the arm 82 carrying the hammer 27. In the same way hammers 28 and 29 are operated by the pins on the pin disc 76, the arrangement of the various pins on the pin discs being such as to provide for a definite sequence of operation of the hammers to produce a desired tone series. As mentioned above, the pin discs are readily removable so that if desired they may be replaced by other discs having different arrangements of pins to produce a different tone sequence upon operation.

The electric motor is arranged so that it will continue in operation until a predetermined sequence of hammer movements has taken place and will then automatically stop. It will be noted that the shaft 74 carries a collar 90 which is loosely rotatable on the shaft and which is provided with opposed slots 91 at its end, the shaft 74 being provided with a transversely extending pin 92 positioned within the slots mentioned. The slots 91 are somewhat larger than the diameter of the pin so that only limited rotational movement of the collar 90 on the shaft 74 is permitted, endwise movement being prevented by the pin 92 and a sleeve 93 secured to the shaft. A spiral spring 94 is connected at one end to a stud 95 on the collar and at its other end to the pin 92, this spring acting normally to hold the side 96 of the notch 91 against the pin 92 in a yielding manner. In other words it urges the collar 90 in a counterclockwise direction as shown in Fig. 6 with relation to the shaft 74. On the collar 90 is a flange 97 which is notched at 98, the notch normally receiving a downturned end 99 of the armature 56 as shown in Fig. 6, when the device is stationary. When the magnet coil 55 is energized by pressing on the push button 54, the armature 56 is drawn upwardly and its end 99 is pulled up out of the notch 98 thus permitting the shaft 74 to be rotated by the motor, the end 99 of the armature riding on the cylindrical surface of the flange 97 until it again drops into the notch 98. It will be seen that the armature 56 will be held in its up position so as to maintain the electrical contact between the contact fingers 50 and 51 even though the push button 54 is only closed instantaneously. The energizing circuit of the electric motor will thus be maintained until the shaft 74 rotates practically one complete revolution, and during this time it will be understood that the various pins on the pin discs 75 and 76 will cause the successive operation of the chime hammers in a predetermined manner depending upon the arrangement of the pins in the pin discs.

At about the end of a complete cycle of operations the slot 98 will be in position to receive the downwardly extended end 99 of the armature 56, and the shaft 74 will be moving counterclockwise as viewed in Fig.

7 at the time the armature moves down to de-
energize the motor circuit. The inertia of
the rotating parts will cause the shaft 74 to
rotate through some little angle after the
motor has been deenergized thus winding
up the spring 94 a little bit bringing the col-
lar 90 into the relationship shown in Fig. 8,
with respect to the shaft 74. The shaft 74
will be positively stopped with the collar
10 in this position, and with the armature end
99 engaging the right-hand side of the notch
98, see Fig. 6. As the collar 90 is tensioned
in a counterclockwise direction, at the end
of a complete cycle of operations, as soon as
15 the push button 54 is closed again and the
magnet coil 55 energize again to attract its
armature, the collar 90 will spring forward,
or in a counterclockwise direction as shown
in Figs. 6 and 7, the very instant that the
20 armature end 99 is removed from the notch.
Without this arrangement, or its equivalent,
closure of the push button 54 for only an
instant might result in the armature end 99
falling back into the notch before the moving
25 parts get started, but with the device shown
the armature end 99 cannot get back into
the notch as the latter is moved forward by
the spring 94 as soon as the armature end
is withdrawn, and the device is thus com-
30 pelled to complete a full cycle of operations
until it is automatically stopped again by
the fall of the armature end 99 into the
notch 98.

It will now be clear that there is an ener-
35 gizing circuit for the motor and a controlling
circuit for the energizing circuit, the con-
trolling circuit being such that it need be
only closed for an instant, or such that it
can be maintained if desired. Thus when
40 the device is used in place of a door bell for
giving a pleasant musical indication when
someone is at the door; the visiting party
need only press the push button 54 for an
instant, or he can press it three or four times
45 in succession but regardless of how the push
button 54 is operated, and regardless of how
long it is maintained in circuit closing position,
the desired signal of the chime will be
produced.

50 All of the electrical wires leading to the
housing or container box are of low voltage
as the transformer 48 is provided at a point
remote from the box, in suitable location.
The box, when recessed in the wall, may have
55 outlet holes 100 preferably back of the face
of the wall, through which the wires leading
to the electric motor and the magnet coil ex-
tend; the connecting wires being of low volt-
age may comprise an ordinary three-wire
60 cable having the usual flexible insulation.

The chime housing for the operating mech-
anism, of course, need not be recessed in the
wall in the manner shown in Fig. 2. Fig.
11 shows the chime mechanism unit adapted
65 to be attached externally to any suitable sup-

port. 103 designates a wall or other support
to which the chime housing is fastened. In
this case the chime housing embodies a
flanged supporting plate 104, the laterally ex-
70 tends flanges 105 of which may be screwed
to the support 103. The supporting plate is
preferably of substantially flattened U-shape,
and its larger face or wall 106 serves as a
support for the chime tubes 107 and also for
75 the hammer operating mechanism 108, the
side plates 109 of which may be secured di-
rectly to the face 106 by means of the angle
pieces 110. The striking noses of the ham-
mers operate through holes in the face 106
80 just as they do through the cover plate 20
in the form of the invention first described.
As the chime tubes 107 are hung from the
stud 111 connected directly to the face 106,
it will be understood that the relationship
85 of the chimes with respect to the hammers
is not disturbed when the casing cover 112
is opened. This cover 112 is preferably
hinged at 113 so as to swing about a vertical
axis to provide access to the chime operating
90 mechanism, but is normally closed against
the face 106, being retained in this position
to protect the operating mechanism from
dust and from injury by a screw 114 the
inner end of which is adapted to be threaded
95 into the face 106. Preferably a top strip
of metal 115 extends over the chime tubes
at the top of the supporting plate 104, being
removably fastened in any suitable manner
as by a suitable snap connection at the upper
100 sides of that portion of the supporting plate
which projects out away from the wall.

While the forms of apparatus herein de-
scribed constitute preferred embodiments of
the invention, it is to be understood that the
invention is not limited to these precise forms
of apparatus, and that changes may be made
105 therein without departing from the scope of
the invention which is defined in the append-
ed claims.

What is claimed is:

1. An electrically driven chime of the class
described, comprising chime sounder means,
hammer means for said chime sounder means,
a rotatable disc operatively connected to said
hammer means, a shaded pole induction mag-
net cooperatively associated with said disc,
115 and means for controlling the energization
of said magnet to obtain a predetermined
sequence of hammer movements.

2. An electrically driven chime of the class
described comprising a housing, a series of
chime members supported exteriorly of said
housing, hammers for said chime members,
means within said housing for operating said
hammers, said housing having a wall between
120 the chime members and the hammer operating
mechanism provided with holes through
which the ends of the hammers project into
engagement with the chime members.

3. An electrically driven chime of the class

- described comprising a housing, a series of chime members supported exteriorly of said housing, hammers for said chime members, means within said housing for operating said hammers, said housing having a wall between the chime members and the hammer operating mechanism provided with holes through which the ends of the hammers project into engagement with the chime members, said hammers when in normal position being in close setting relation to said housing holes to provide a substantially dust-proof housing.
4. A chime of the class described comprising a chime member, means for suspending said chime member, said suspending means comprising a hanger member in looped engagement with said chime member, and a spreader member adapted to space said hanger member from the top of said chime member.
5. A chime of the class described comprising a chime member, means for suspending said chime member, said suspending means comprising a hanger member in looped engagement with said chime member, and a spreader member of substantially triangular shape, said spreader member having a face extending transversely of the chime member and of greater length than the width of said chime member, said spreader member being adapted to provide a guide for the exposed length of said hanger member.
6. An electrically driven chime of the class described, comprising chime sounder means, an electric motor, mechanism driven by said motor for causing the striking of the chime sounder means, an energizing circuit for said motor, a manually operated switch controlling said energizing circuit, and means for maintaining said energizing circuit closed for a predetermined interval even though the manual switch is operated only instantaneously.
7. An electrically driven chime of the class described, comprising chime sounder means, an electric motor, mechanism driven by said motor for causing the striking of the chime sounder means, an energizing circuit for said motor, means for maintaining said energizing circuit for a predetermined constant interval, and a manually controlled circuit for closing said energizing circuit.
8. An electrically driven chime of the class described, comprising chime sounder means, an electric motor, mechanism driven by said motor for causing the striking of said chime sounder means in a definite predetermined manner, an energizing circuit for said motor including a switch, a controlling circuit for said energizing circuit including a magnet for operating said switch, a second switch in said controlling circuit, and means operated by said motor for maintaining said first-named switch closed for a predetermined interval.
9. An electrically driven chime of the class described, comprising chime sounder means, a low voltage alternating current motor, mechanism driven by said motor for striking the chime sounder means, an energizing circuit for said motor, a manually controlled circuit controlling the closing of said energizing circuit, and means automatically operating after a predetermined cycle of operations of the motor for interrupting said energizing circuit.
10. An electrically driven chime of the class described, comprising chime sounder means, hammer means for striking said chime sounder means, a rotatable disk, a shaded pole induction magnet cooperatively associated with said disk, a series of pins operatively connected to said disk for controlling the operation of said hammer means, and manual means for controlling the energization of the magnet.
11. An electrically driven chime of the class described, comprising a series of chime members of different tone, a rotatable disk, a shaded pole induction magnet cooperatively associated with said disk and adapted for low voltage alternating current energization, a series of hammers for said members, mechanism operated by said disk for successively operating said hammers in a predetermined definite manner, means supporting all of said elements inside a building, and means outside the building controlling the energization of said magnet.
12. An electrically driven chime of the class described, comprising a chime member, an electric motor, a striker for said chime member, mechanism operated by said motor for controlling said striker in a predetermined definite manner, an energizing circuit for said motor, a manually controlled circuit for controlling said energizing circuit, means operated by said motor for maintaining said energizing circuit closed until a cycle of operations is completed and a spring for moving said means instantaneously when the manually controlled circuit is energized and before the motor starts operating.
13. An electrically driven chime of the class described, comprising a series of chime members of different tone, an electric motor, a series of hammers for said members, mechanism operated by said motor for successively operating said hammers in a predetermined definite manner, an energizing circuit for said motor including a switch and a controlling coil therefor, a manually controlled circuit including said controlling coil for closing said energizing circuit, holding means for holding said energizing circuit switch closed, a spring and a stop member, said stop member being operably connected by said spring to said motor so that immediately upon ener-

- gization of said coil said stop member is said hammer means being extended away from its striking and beyond its pivotal support and engaging said stop in a yielding manner just before the hammer means is in contact with the sounder means. 70
14. An electrically driven device of the class described, comprising sounder members of different tones, an electric motor for operating said sounder members, an energizing circuit for said motor, a motor starting switch, a spring, and a mechanical stop for 10 positively stopping said electric motor through said spring after a completed cycle of operations, the spring acting to instantly release said motor when the manual starting switch is closed. 75
15. An electrically driven device of the class described, comprising a casing, sounder members of different tone supported externally on said casing, an electric motor supported in said casing, mechanism in said casing 20 driven by said motor for operating said sounder members, an energizing circuit for said motor including a pair of contact fingers, an electromagnet having an armature controlling said contact fingers, a controlling 25 circuit for energizing said electromagnet, and means operable instantly upon energization of said controlling circuit for maintaining said contact fingers in motor energizing relationship until a predetermined operation of 30 the motor has been completed. 80
16. An electrically driven device of the class described, comprising sounder members of different tone, an electric motor, mechanism driven by said motor for operating said 35 sounder members, an energizing circuit for said motor including a pair of contact fingers, an electromagnet having an armature controlling said contact fingers, a remotely positioned manually controllable switch for energizing said electromagnet, spring pressed 40 means for maintaining said armature in operative position after closing of said remotely positioned switch until after a predetermined cycle of operation of the motor, said means 45 being adapted to automatically positively stop the motor and energize the spring at the end of the predetermined cycle of operation. 85
17. An electrically driven chime of the class described, comprising a series of chime 50 members of different tone, an electric motor, a shaft operated by said motor and having several series of hammer operating pins, a pivotally supported hammer for each chime member operated by said pins in a predetermined manner so as to be raised and permitted to drop freely under the force of gravity successively in a definite predetermined 55 manner, and means controlling the operation of said electric motor. 90
18. An electrically driven chime of the class described, comprising chime sounder means, hammer means cooperating with said sounder means, means for freely pivotally supporting said hammer means, an electric 60 motor for raising said hammer means, a stop, 95
19. An electrically driven chime of the class described comprising an induction disk alternating current motor, a series of chime members operated by said motor, a casing mounted in a building wall supporting said chime members and enclosing said motor, and a remotely located switch provided outside the building for energizing said motor. 100
20. An electrically driven chime of the class described comprising a housing having a front cover plate, a series of chime sounders externally hung on said plate, chime operating mechanism detachably fastened within said housing and including an electric motor and striking mechanism operated by said 105 motor. 110
21. An electrically driven chime of the class described, comprising chime sounder means, hammer means cooperating with said sounder means, means for pivotally supporting said hammer means, and frictional means providing rubbing engagement with said hammer means for braking the action of said hammer means as it strikes the sounding means to prevent sounding a false note. 115
22. A chime of the class described comprising a supporting plate, a series of chime members, chime supports adjustably mounted on said plate and providing for adjustment of the positions of the chime members toward 100 and away from the plate, and mechanism supported on the opposite side of said plate from the chime members for operating said chime members. 120
23. A chime of the class described comprising a supporting plate, chime members supported from one side of said plate, a frame attached directly to the other side of said plate, mechanism supported in said frame including an electric motor and motor operated chime strikers, and an enclosing casing around said mechanism. 125
24. A chime of the class described comprising a supporting plate, chime members mounted on said plate, a frame supported on the opposite side of said plate and comprising spaced frame members extending transversely of said plate, a motor driven shaft journaled in said frame, wheels mounted on said shaft on opposite sides of said frame and externally of said frame members, pin series on said wheels, and chime strikers operated by said pin series. 130
25. An electrically driven chime of the class described comprising a housing, a series of chime sounders externally hung on said housing, electrically controlled means within said housing, and a chime cover fixed to said housing, said chime cover extending 135

over and enclosing only the top ends of the chime sounders.

26. An electrically driven chime of the class described comprising a housing, a series of chime sounders externally hung on said housing, chime operating mechanism mounted within said housing and including an electric motor and striking mechanism controlled by said motor, and a chime cover fixed to said housing, said chime cover extending over and enclosing the top ends of the chime sounders.

27. An electrically driven chime comprising chime sounder means, an electric motor controlling the operation of said sounder means in a predetermined manner, an energizing circuit for said motor including a pair of contact fingers, an alternating current electromagnet having a pivoted armature controlling said contact fingers, a controlling circuit for said electromagnet, means for maintaining said armature in attracted position for a predetermined cycle of motor operation, and means for relative adjustment of the electromagnet and armature.

In testimony whereof I hereto affix my signature.

GISBERT LUDOLF BOSSARD.
